UNITED STATES PATENT OFFICE.

JOSEPH R. VILLARD, OF ROCHESTER, NEW YORK.

AUTO-SIGNAL.

1,368,772.

Specification of Letters Patent. Patented Feb. 15, 1921.

Application filed October 20, 1920. Serial No. 418,330.

To all whom it may concern:

Be it known that I, JOSEPH R. VILLARD, citizen of the United States, residing at Rochester, in the county of Monroe and State of New York, have invented certain new and useful Improvements in Auto-Signals, of which the following is a specification.

The object of this invention is to provide 10 a new and improved form of auto signal.

This and other objects of the invention will be fully illustrated in the drawings, described in the specification and pointed out in the claims at the end thereof.

15 In the drawings,

Figure 1 is a side elevation of my improved auto signal with the casing partly broken away.

20 Fig. 2 is a top plan view of the signal extended with the top of the casing partly broken away.

Fig. 3 is a side elevation of the signal withdrawn into the casing.

25 Fig. 4 is an end elevation of the signal and its casing viewed from the left of Fig. 3.

Fig. 5 shows a modified form of my invention, operated by an electric motor.

30 Fig. 6 is a detail view of the motor and lead screw for operating the signal.

Fig. 7 is a diagrammatic view of the signal with its operating mechanism extended so that it can be moved in and out from either side of the car.

35 In the drawings, like reference numerals indicate like parts.

In the drawings, reference numeral 1 indicates the casing having a base or angle plate 2 on the side thereof which carries a 40 stud 3, which extends through the side 4 of the car so that it may be clamped in place by the nut 5. Inside of the casing is a series of lazy tongs. In this instance five long, swinging links 6 of the series on one side

45 are shown in folded up position in Fig. 1. A similar set of links are provided on the other side. On the base plate is a stationary link 7. The stationary link 7 is slotted at the top, as indicated at 8, and in this 50 slot slides a pin 9 that is attached to one of the long links on the other side of the series. To the bottom of the stationary link 7, one of the swinging links 6 is pivotally attached and this link is connected to the handle 10 55 by which it may be moved open and shut,

the open position of the handle 10 being shown in dotted lines and the shut position being shown in full lines. The top of the casing is slotted as shown in Fig. 1 to permit the swinging of the handle. Connected 60 to the top and bottom joints of the links of the lazy tongs I provide the plates 11, 12, 13 and 14, which plates are fitted to telescope on each other. Each pair of plates is pivotally connected directly to the links at 65 the bottom as indicated at 15. The rear edge of the plate is turned up into a sleeve 16 which acts as a guide at the top to receive the stem 17, attached to the pin 18, which holds together the upper end of the 70 links of the front and back series. As the links are closed up to the full line position shown in Fig. 1, these stems 17 rise in the guides and maintain firm connection with the plates so that the plate being held at 75 both the top and bottom, is kept in an upright position. As the lazy tongs are extended, the stems 17 move down into the sleeve as the links swing on the centers at the bottom. Each pair of these plates are 80 thus fastened to the joints of the long links at both the top and bottom and are moved out and in as the links are moved to open and shut position. On each of these plates I place a letter so that the letters collectively 85 spell a word, the word "Stop" being so indicated in Fig. 1. These letters will ordinarily be painted on the plates and to prevent these painted letters from being rubbed off by the plates rubbing against each other, 90 I provide for holding the plates apart in the zone occupied by the letters. For this purpose, I provide small rollers 19 and 20 at the top and bottom of each plate at the forward edge. The plates overlap each 95 other so that between the links of the lazy tongs and the overlapping of the plates themselves, the plates are held firmly in position when extended.

To reach the handle 10 shown in Fig. 1, 100 the driver or operator would have to reach outside of the car, and to permit the operation from within the car, I provide an opening 21 in the base and the opening 22 in the side of the car. Through these openings 105 extends the link 23 which engages with the handle 24 pivoted at 25 on the inside of the car. The other end of the link 23 is connected to the lazy tongs. In this case, the handle 10 outside of the car is omitted. By 110

the movement of the handle 24 the signal is extended or withdrawn as the operator may desire.

In Fig. 7 I have shown the hand connections by which the signal can be operated from either side of the car. In this case, I mount a handle 40 on the right hand side of the car, which handle is connected by a link 41 to the handle 24 on the left hand side 10 of the car so that both of these handles will operate in unison and the signal can be operated from either side of the car.

To operate the signal electrically, I provide in the top of the casing 1 a motor 30 having a shaft 31 which drives a lead screw 32 through the universal joint 33. The screw 32 is blank at each end, the thread being turned down therefrom. On the lead screw I provide a nut 34 having a swivel connection with the link 35. At each end of the screw I provide a washer 36 and spring 37 which normally presses the washer toward the end of the thread. This washer engages with the link 35 and holds the nut up 25 against the end of the thread. When the circuit is closed to extend the signal, the motor is driven to turn in one direction causing the thread of the screw to engage with the nut at the right and move the nut to the left where it passes off to the end of the thread and by the thread is pushed against the washer 34 compressing the spring 37. The expansion of the spring 37 will hold the nut against the end of the 30 thread and when the screw turns in the reverse direction, the thread will engage the nut and move it to the right until it passes off of the thread compressing the spring 37 at the other end of the screw. In this way, 35 the thread will engage the nut at either end and move it the correct distance irrespective of the time when the motor stops each time it is started. As the link 35 moves to the left or right, the outer end of the screw falls 40 and rises, this being permitted by the universal joint 33.

I claim:

1. An auto signal having a series of lazy tongs, a series of overlapping plates fastened 50 to the links of said tongs, said plates being telescoped when the links are drawn together and being drawn out when the links are extended, said plates being pivotally connected to the links on one side and having 55 a sliding engagement with the links on the other side.

2. An auto signal having a series of lazy tongs, a series of overlapping plates fastened to the links of said tongs, said plates being 60 telescoped when the links are drawn together and being drawn out when the links are extended, said plates being pivotally

connected to the bottom of the links on one side and having a sleeve formed on one edge with which the links make a sliding connection. 65

3. An auto signal having a series of lazy tongs, a series of overlapping plates fastened to the links of said tongs, said plates being telescoped when the links are drawn together and being drawn out when the links are extended, rollers on the forward edges of the plate that make rolling contact with the next adjacent plate and hold the plates from sliding contact. 70

4. An auto signal having a series of lazy tongs, a series of overlapping plates fastened to the links of said tongs, said plates being telescoped when the links are drawn together and being drawn out when the links are extended, a lever connected to one of said lazy tongs, a lead screw connected thereto by which the lever is moved forward and back, means for rotating the lead screw in either direction. 75

5. An auto signal having a series of lazy tongs, a series of overlapping plates fastened to the links of said tongs, said plates being telescoped when the links are drawn together and being drawn out when the links are extended, a lever connected to one of said lazy tongs, a lead screw connected thereto by which the lever is moved forward and back, means for rotating the lead screw in either direction, said screw being mounted 80

85 to swing as the lever is driven.

6. An auto signal having a series of lazy tongs, a series of overlapping plates fastened to the links of said tongs, said plates being telescoped when the links are drawn together and being drawn out when the links are extended, a lever connected to one of said lazy tongs, a nut on said lever, a lead screw 90 connected thereto by which the lever is moved forward and back, means for rotating the lead screw in either direction, said screw being mounted 95 to swing as the lever is driven.

100

7. An auto signal comprising a casing, a series of lazy tongs, adapted to move in and out of said casing, a series of overlapping plates arranged in pairs, fastened to the links of said lazy tongs with the inner ends thereof and on either side of said links, the sides of said casing being adapted to force 110 the outer end of a pair of said plates toward each other and exert a yielding pressure against the preceding and succeeding pair of plates and hold said plates in parallel alignment with the links of said lazy 115 tongs.

120 In testimony whereof I affix my signature.

JOSEPH R. VILLARD.
